SAFETY SPINDLE

Max Hayman and Gustave Heyman,
Battle Creek, Mich.

Application March 25, 1948, Serial No. 16,926

6 Claims. (Cl. 129—23)

1

This invention relates to improvements in a safety paper spindle.

The principal objects of this invention are;

First, to provide a novel form of spindle for receiving record papers, bills and the like in which the piercing end of the paper receiving spike is protected by a guard member for preventing the user's hand from becoming engaged with the spike and in which the guard member is easily swingable out of guard position for removal of papers from the spike.

Second, to provide a paper spindle with a guard member which is spring urged to swing in the plane of the spike to operable guarding position.

Third, to provide a novel and inexpensive form of spring mount for the swinging member of a safety paper spindle.

Fourth, to provide a safety paper spindle with a spring mounting for the guard member which is easily and securely fastened to the guard member without the use of tools so that the spindle may be packed in disassembled condition to obtain saving in shipping space and can be easily assembled by the users.

Fifth, to provide a safety spindle which can be manufactured at extremely low cost with a minimum number of parts.

Other objects and advantages pertaining to the details and economies of our invention will be apparent from the following description and claims.

The drawings of which there is one sheet illustrate a preferred form of our safety spindle.

Fig. 1 is a side elevational view of the spindle in erected operative position.

Fig. 2 is a plan view of the under side of the spindle.

Fig. 3 is a fragmentary vertical cross sectional view through the base of the spindle taken along the line 3—3 in Fig. 2.

Fig. 4 is a fragmentary perspective exploded view of the guard member and its supporting spring employed in the spindle.

The spindle consists generally of a base 1 on which is mounted the paper impaling spike 2 and a swingable spring mounted guard rod 3. The upper end of the guard rod is turned forwardly over the top of the spike 2 and provided with a guard nob 4 preferably formed of plastic or other moldable material. The nob 4 is shaped with a rearwardly and downwardly inclined under surface as at 5 to guide papers over the end of the spike. The nob is spaced from the end of the spike so as to substantially prevent the entry of the user's hand or fingers between the nob and spike as is indicated in Fig. 1.

2

The upper surface of the base 1 is shaped to provide an attractive appearance but is preferably formed with downwardly extending marginal flanges 6 defining a recess on the under side of the base. The under side of the base is formed with a pair of laterally spaced depending ears 7 and a pair of laterally spaced bosses 8 positioned longitudinally forwardly of the ears 7. Forwardly of the bosses 8 and along the center line between the ears and bosses the base is provided with a thickened portion 9 defining a tapped aperture 10. The flanges 6 are thickened at the corners of the base as at 11 and define downwardly opening apertures 12 for receiving the shanks of rubber pads 13 which form nonmarring feet for the spindle.

The top wall of the base defines a longitudinally extending slot 14 opening to between the ears 7 and adapted to pass the lower end of the guard rod 3. The lower end of the guard rod is partially cut away on its rear side as at 15 and is received through a slot 16 in the rear end of a leaf spring 17. The rear end of the spring 17 is downwardly flanged as at 18 to bear against the vertical surface of the cut away portion 15 and forwardly turned ears 19 on each side of the flange 18 are arranged to engage the lower end of the guard rod and prevent its tilting relative to the spring 17. The slot 16 is formed in the spring 17 by striking downwardly the tongue 20, the rear edge of which engages and grips the lower end of the guard rod to hold the rod in engagement with the spring.

The forward end of the spring 17 extends between the bosses 8 on the base and is secured against the under side of the base by staking or swaging over the opposed edges of the bosses 8 as at 21 (see Fig. 2). The forward end of the spring 17 is provided with an upwardly turned ear 22 received in a recess 23 provided therefor in the under surface of the base to the rear of the thickened portion 9.

The base is conveniently formed as a casting and preferably is completed to include the feet 13, spring 17 and tapped aperture 10. The spindle can be packed and shipped with the spike and guard rod disassembled to permit the use of a small carton. The user can thread the lower end of the spike into the aperture 10 and push the lower end of the guard rod through the slot 14 in the base and the slot in the spring 17. The spindle is then erected and ready for use. The guard rod can be tilted rearwardly as shown in Fig. 1 to permit removal of papers from the spike. Flexing of the spring permits this tilting and the forward end of the slot 14 forms

a stop for limiting forward tilting of the guard rod.

We have thus described a highly practical form of our paper spindle which is extremely inexpensive to manufacture and easy and safe to use and unload. We intend this description to be an example only of our spindle as certain modifications of its structure can readily be made to suit the taste of the manufacturer without departing from the scope of the invention. Obviously the spike rather than the guard rod could be yieldingly mounted if desired.

Having thus described our invention, what we claim as new and desired to secure by Letters Patent is:

1. A safety spindle including a base having spaced bosses on the under side thereof, a spike, a guard rod, said base defining a tapped aperture receiving the lower end of said spike and a slot spaced from said aperture tiltably receiving the lower end of said guard rod, a leaf spring having one end secured to the bottom of said base by staking over said bosses, the free end of said spring projecting under the end of said slot and having a down turned flange, a finger struck downwardly from the free end of said spring to define a second slot the end of which overlaps the end of said slot in said base, the lower end of said guard rod being notched and received through said slot in said spring with said flange bearing against the edge of said notch and with said tongue springably gripping the opposite side of said guard rod from said notch, ears turned from the lower edge of said flange and arranged to engage the side of said guard rod, a forwardly turned upper end on said guard rod, and a guard head secured to said forwardly turned end in closely spaced relationship with the upper end of said spike.

2. A safety spindle including a base having spaced bosses on the under side thereof, a spike, a guard rod, said base defining a tapped aperture receiving the lower end of said spike and a slot spaced from said aperture tiltably receiving the lower end of said guard rod, a leaf spring having one end secured to the bottom of said base by staking over said bosses, the free end of said spring projecting under the end of said slot and having a down turned flange, a finger struck downwardly from the free end of said spring to define a second slot the end of which overlaps the end of said slot in said base, the lower end of said guard rod being notched and received through said slot in said spring with said flange bearing against the edge of said notch and with said tongue springably gripping the opposite side of said guard rod from said notch, a forwardly turned upper end on said guard rod, and a guard head secured to said forwardly turned end in closely spaced relationship with the upper end of said spike.

3. A safety spindle including a base defining a recess on the underside thereof, a spike, a guard rod, said base defining a tapped aperture receiving the lower end of said spike and a slot spaced from said aperture tiltably receiving the lower end of said guard rod, a leaf spring having one end secured to the bottom of said base by staking over a portion of the side of said recess, the free end of said spring projecting under the end of said slot and having a down turned flange, a finger struck downwardly from the free end of said spring to define a second slot the end of which registers with the end of said slot in said base, the lower end of said guard rod being

notched and received through said slot in said spring with said flange bearing against the edge of said notch and with said tongue springably gripping the opposite side of said guard rod from said notch, a forwardly turned upper end on said guard rod, and a guard head on said forwardly turned end in spaced relationship with the upper end of said spike.

4. A safety spindle including a base defining a recess on the underside thereof, a spike, a guard rod, said base defining a tapped aperture receiving the lower end of said spike and a slot spaced from said aperture tiltably receiving the lower end of said guard rod, a leaf spring having one end secured to the bottom of said base by staking over a portion of the side of said recess, the free end of said spring projecting under the end of said slot and having a down turned flange, a finger struck downwardly from the free end of said spring to define a second slot the end of which registers with the end of said slot in said base, the lower end of said guard rod being received through said slot in said spring with said tongue springably gripping the side of said guard rod, a forwardly turned upper end on said guard rod, and a guard head on said forwardly turned end in spaced relationship with the upper end of said spike.

5. A safety spindle including a base having a recess on the underside thereof, a spike member, a guard rod member, said base defining a tapped aperture receiving the lower end of one of said members and a slot spaced from said aperture tiltably receiving the lower end of the other of said members, a leaf spring having one end secured to the bottom of said base by staking over a portion of the wall of said recess, the free end of said spring projecting under the end of said slot and having a down turned flange, a finger struck downwardly from the free end of said spring to define a second slot the end of which registers with the end of said slot in said base, the lower end of the other of said members being received through said slot in said spring with said tongue springably gripping the side of said other member, ears turned from the lower edge of said flange and arranged to engage the side of said other member, and a forwardly turned upper end on said guard rod terminating in closely spaced vertical relationship with the upper end of said spike.

6. A safety spindle including a base having a recess on the underside thereof, a spike member, a guard rod member, said base defining a tapped aperture receiving the lower end of one of said members and a slot spaced from said aperture tiltably receiving the lower end of the other of said members, a leaf spring having one end secured to the bottom of said base, the free end of said spring projecting under the end of said slot and having a flange, a finger struck downwardly from the free end of said spring to define a second slot the end of which registers with the end of said slot in said base, the lower end of the other of said members being received through said slot in said spring with said tongue springably gripping the side of said other member, and a forwardly turned upper end on said guard rod terminating in closely spaced vertical relationship with the upper end of said spike.

MAX HAYMAN.

GUSTAVE HEYMAN.
